UNITED STATES PATENT OFFICE.

WALTER HUG, OF MEDFORD, WISCONSIN.

CAN-COVER LOCK.

Application filed May 8, 1925. Serial No. 28,833.

To all whom it may concern:

Be it known that I, WALTER HUG, a citizen of the United States, residing at Medford, in the county of Taylor, State of Wisconsin, have invented certain new and useful improvements in Can-Cover Locks, of which the following is a specification.

This invention relates to a can cover lock especially adapted for use on milk cans or 10 the like.

The object of the invention resides in the provision of a can cover lock adapted to securely hold the cover to the can against accidental displacement, the lock being 15 readily releasable when it is desired to remove the cover from the can and the lock and cover being so constructed and organized as to facilitate the handling of the cover and the manipulation of the locking 20 mechanism, the lock being released for the removal and application of the cover when the handle member of the cover is gripped in the ordinary way.

A further object resides in the provision 25 of a can cover lock having the advantages and capacities mentioned and which is of simple and durable construction, reliable and effective in operation and easy and comparatively inexpensive to manufacture.

Other objects and advantages reside in 30 certain novel features of the construction, arrangement and combination of parts which will be hereinafter more fully described and particularly pointed out in the 35 appended claims, reference being had to the accompanying drawings forming a part of this specification, and in which:

Figure 1 is a view in transverse vertical section taken on the line 2—2 of Figure 2, 40 the cover plate or top plate being shown in position,

Figure 2 is a view in top plan with the top plate or cover plate removed, and

Figure 3 is a view in transverse vertical 45 section on the line 3—3 of Figure 1.

Referring to the drawing, the numeral 1 designates a milk can having a cylindrical neck 2, the upper end of which is flared upwardly, as at 3, in the usual way.

A cover designated generally at 4, is provided and has a cylindrical body portion 5, the lower end of which is closed by a plate 6. The upper end of the cylindrical body portion has integrally formed therewith a flaring extension 7 which terminates in an outwardly directed flange. In assembly the

cover is inserted in the top of the can 1 so that its cylindrical body portion 5 is snugly fitted in the neck 3, its flaring portion 7 is engaged with the flaring portion 3 of the 60 can and its flange 8 rests on the beaded edge 3^a of the flaring portion 3.

A combination handle member and housing, designated generally at 10, is provided and extends transversely of the cover. The 65 combination handle member and housing 10 has a rounded underside 11 shaped to be conveniently gripped and vertical side walls 12. At their ends the side walls 12 have attaching lugs 13 which are designed to fit 70 up against the flaring extension 7 of the cover and to be secured thereto by welding, brazing, riveting, or the like. As shown in the drawings the combination housing and handle member is located entirely within 75 the confines of the cover. Along their upper edges the side walls 12 of the housing are formed with inturned horizontal flanges 14 and at their ends these side walls 12 have up- 80 struck lips 15. A horizontal plate 16 is provided and is fastened to the flanges 14 of the side walls 12 at their centers. A top or 85 cover plate 17 is provided and has down-turned flanges 18 which rest on the flanges 14 of the side walls. The flanges 18 terminate 90 at points adjacent to but spaced from the ends of the plates 17 to provide the spaces necessary to permit the lugs or lips 15 to engage the underside of the cover plate 17 at its ends. Screws 19 are provided for fastening 95 the cover plate 17 in position, the screws coacting with the cover plate and with the plate 16. Since the plate 16 is fastened to the flanges 14 of the side walls 12 the cover plate is indirectly secured to the side 100 walls.

On each side of the center of the housing and handle member 10 a pair of transversely disposed plate-like bearing members 20 are provided. In the bearing members 20 bolts 105 21 are slidably fitted. The outer ends of the bolts may be projected through openings 22 provided in the cover and openings 23 provided in the can, and when projected the bolts lock the cover to the can. When retracted the bolts are contained entirely within the cover and permit the cover to be lifted from the can or to be applied thereto.

Retractable coil springs 24 are provided for the purpose of projecting the bolts 21 110 and these retractile coil springs preferably are located above the bolts. One end of

each coil spring 24 is fastened to a fixed bracket 25 which may be integrally formed with one of the plate-like bearing members 20. The other end of each coil spring 24 is fastened to a bin 26 rigidly connected with its bolt 21. The springs 24 are tensioned to project the bolts 21 and yieldably hold the same projected in the position shown in Figure 1.

10 In order to provide for the convenient release or retraction of the bolts simultaneously with the lifting of the cover or with its manipulation, an elongated and curved operating plate 30 is provided and is shaped 15 to be conveniently grasped by the hand and to fit snugly and flush up against the underside of the casing when moved to position to release the bolts. A hollow or tubular post 31 is integrally formed with the 20 operating plate 30 and is slidably fitted in a sleeve bearing 32 disposed within the housing 10 and connected to the bottom wall of the housing. Bell crank levers, designated generally at 33, are provided, there 25 being one bell crank lever for each bolt. The bell crank levers are fixed on the rock shafts 34 rotatably mounted in bearings provided therefor in the side walls 12 of the housing and handle member 10. Each bell 30 crank lever 33 has an arm 35 pivotally connected by a pivot pin 36 to the slotted end of its bolt 21 and each bell crank lever also has an arm 37 accommodated in an elongated slot 38 formed in the sleeve bearing 32 and 35 through a slot 39 formed in the plate 16 and operating in the slot 40 provided in the tubular post 31. With this arrangement when the combined housing and handle member 10 is grasped in the hand, as it conveniently may be, the operating plate 30 is 40 grasped by the fingers so that when the grip is tightened the plate 30 will be brought up flush against the underside of the member 10. This movement of the plate raises the post 31 in its sleeve bearing 32 and the upward movement of the post 31 is transmitted 45 through the bell crank levers 33 to the bolts 21 since the lower walls of the slots 40 engage the arms 37 of the bell crank levers to 50 swing them and their rock shafts in such a way as to cause the arms 35 which are pivotally connected to the bolts to swing inwardly and consequently cause the bolts 21 to slide inwardly. In lieu of an ordinary pivotal 55 connection between the arms 35 and the bolts 21, a pin and slot connection may be provided if found desirable, but since the arms 35 swing through a small arc it is believed that a pivotal connection will be 60 sufficient.

I claim:

1. In a can cover lock, a combined handle member and housing located within the cover, extending transversely thereof and secured at its ends to diametrically op-

posed portions of the cover, said combined handle member and housing being shaped to be gripped by the hand, a pair of bolts within the housing, means for mounting the bolts for operative movement, the bolts being projectible and being adapted to lock the cover in position and being retractible to permit of release of the cover, springs for projecting the bolts, means for retracting the bolts comprising an elongated and rigid operating plate designed to be gripped with the combined handle and housing in applying and removing the cover and shaped to snugly fit the underside of the housing when pulled upwardly thereagainst, and means for interconnecting the plate and housing and also the plate and bolts for constraining the plate to partake of rectilinear movement back and forth toward and away from the combined handle member and housing and for positively transmitting the movement of the plate to the bolts.

2. In a can cover lock, a combined handle member and housing located within the cover, extending transversely thereof and secured at its ends to diametrically opposed portions of the cover, said combined operating handle member and housing having its lower portion rounded and being shaped to be gripped by the hand, a pair of bolts within the housing, means for mounting the bolts for sliding movement, the bolts being projectible and being adapted to lock the cover in position and being retractible to permit of release of the cover, springs for projecting the bolts, means for retracting the bolts and comprising an elongated and curved operating plate designed to snugly fit the under side of the housing when pulled upwardly, and motion transmission means between the plate and the bolts comprising a tubular post connected with the operating plate, a bearing sleeve secured to the housing and disposed therein, said post being slidably fitted in the sleeve, bell crank levers mounted within the housing, each bell crank lever having an arm connected to its bolt and having another arm with which the post co-acts, the post and its bearing sleeve being slotted to engage and accommodate the arms of the bell crank levers with which they co-act.

3. In a can cover lock, a combined handle member and housing located within the cover, extending transversely thereof and secured at its ends to diametrically opposed portions of the cover, said combined operating handle member and housing having its lower portion rounded and being shaped to be gripped by hand, a pair of bolts within the housing, means for mounting the bolts for sliding movement, the bolts being projectible and being adapted to lock the cover in position and being retractible to permit of release of the cover, springs for projecting the

- bolts, means for retracting the bolts and comprising an elongated and curved operating plate designed to snugly fit the underside of the housing when pulled upwardly, 5 motion transmission means between the plate and the bolts comprising a tubular post connected with the operating plate, a bearing sleeve secured to the housing and disposed therein, said post being slidably fitted in 10 the sleeve, bell crank levers mounted within the housing, each bell crank lever having an arm connected to its bolt and having another arm with which the post co-acts, the post and its bearing sleeve being slotted to engage 15 and accommodate the arms of the bell crank levers with which they co-act, said housing having a removable top plate to facilitate access to the locking mechanism.
4. In a can cover lock, a combined handle member and housing located within the cover, extending transversely thereof and se- 20 cured at its ends to opposite portions of the cover, said combined operating handle member and housing having its lower portion rounded and being shaped to be gripped by the hand, a pair of bolts within the housing, means for mounting the bolts for operative movement, the bolts being projectable to lock the cover in position and retractile to permit of release of the cover, springs for projecting the bolts and means for retracting the bolts comprising an elongated curved and rigid operating plate designed to snugly fit the underside of the housing when pulled upwardly, and motion transmission means 25 between the plate and bolts comprising a post connected to the plates and operating in the housing, and levers fulcrumed in the housing and having arms connected to the post and arms connected to the bolts. 30
